UNITED STATES PATENT OFFICE

2,436,636

INSTRUMENT CURRENT TRANSFORMER

Franklin R. D'Entremont, Lynn, Mass., assignor
to General Electric Company, a corporation of
New York

Application July 14, 1944, Serial No. 544,985

6 Claims. (Cl. 175—358)

1

My invention relates to electromagnetic induction apparatus and more particularly to core clamping and supporting arrangements for such apparatus, and it is a general object of my invention to provide an improved electromagnetic induction apparatus with a core clamping and supporting structure which is simple in design and which will facilitate the manufacture of the apparatus.

A further object of my invention is to provide an improved core clamp and base structure for an electromagnetic induction apparatus.

Further objects and advantages of my invention will become apparent from the following description referring to the accompanying drawing, and the features of novelty which characterize my invention will be pointed out with particularity in the claims annexed to and forming a part of this specification.

In the drawing Fig. 1 is a side view in partial section illustrating a transformer which is provided with an embodiment of my invention; Fig. 2 is an end view of the structure of Fig. 1; Fig. 3 is an exploded perspective view of the core clamp and supporting structure of the transformer of Figs. 1 and 2; Fig. 4 is a perspective view partly broken away illustrating the primary winding which is used with the structure of Figs. 1 and 2; Fig. 5 is an end view of a transformer which is provided with a modification of my core clamp and supporting structure; Fig. 6 is a side view of the structure of Fig. 5; Fig. 7 is a sectional side elevation of the construction illustrated in Figs. 5 and 6 taken along the line 7—7 of Fig. 5; Fig. 8 is a perspective view of the cradle clamp employed in the transformer of Figs. 5 and 6, and Fig. 9 is a modification of the invention of Figs. 1 to 4.

Referring more particularly to Fig. 1 of the drawing I have illustrated an electromagnetic induction apparatus such as a transformer having a core member 1 which is formed in any suitable manner such as by winding a strip of magnetic material into a generally toroidally shaped core member. Surrounding the core member is an insulated secondary winding 2. Since the transformer illustrated in Figs. 1 and 2 has particular application as an instrument current transformer the primary winding is provided by a single bar member 3 illustrated in detail in Fig. 4, which extends through an opening in the core member 1. In order to suitably insulate the high and low voltage winding a tubular shaped insulating member 4 is provided around the primary bar 3 and insulation 5 of

2

any suitable material, such as paper, is built up around the bar on the portions which extend on either side of the insulated secondary winding 2, such insulation 5 provides a relatively high creepage path between the terminal end 6 of the primary winding bar and the insulated secondary winding 2.

In order to provide an improved arrangement for clamping the core as well as providing a supporting base for the apparatus I provide a core clamp construction which includes a member 7 formed of any suitable material such as metal which surrounds the outer surface of the core 1 and follows closely the contour thereof. It will be understood that suitable insulation 8 is provided between the core clamp member 7 and the insulated secondary winding 2. Such insulation will position the core clamp member 7 as well as insulate the secondary winding 2 from the core clamp member 7 and the core 1. In order to bind the core clamp member 7 to the outer surface of the core a bolt 9 is provided which extends through apertures 10 in arm members 11 which are integral with and extend from the core clamp member 7. It will be understood that when the nut 12 is tightened on the end of the bolt 9 the core clamp member 7 will tightly surround the outer surface of the core member. A sleeve 13 is provided around the bolt and between the arms 11 so as to prevent the arms from being forced out of shape when the bolt 9 and nut 12 are tightened. A plate 14 is also provided which is attached to feet members 15 which are integral with and extend in substantially right angles with the arms 11, and the plate 14 and feet 15 may be provided with suitable holes so that the apparatus may be suitably attached to any other apparatus.

In Figs. 5 through 8 I have illustrated a modified type of cradle clamp construction which is employed with a similar core member 1. The cradle clamp being provided with arms 16 and 17 which are adjacent the outer surface of a portion of the core and follow the contour thereof, as is illustrated in Fig. 5. Feet members 18 and 19 are provided which are integral with the arms 16 and 17 so as to provide a space for supporting the apparatus.

As will be seen more particularly in Fig. 7, insulation in the form of flat washers 20 and 21 are provided around the edges of the core and a filler strip of suitable insulating material 22 is provided for surrounding the remainder of the core surface which is not surrounded by the cradle arms 16 and 17. Another insulating strip

23 is provided around the filler strip 22 as well as the core clamp arms 16 and 17, and a layer of the secondary winding 24 may then be distributed through and around the core member. Layer insulation 25 is then provided and a second conducting layer 26 is provided forming a second layer of the secondary winding. Further insulating layers 27 are then provided.

The core clamp and supporting construction described above may be employed with any suitable type of core construction, and in Fig. 9 I have illustrated my invention as applied to a generally toroidally shaped core 28 which is formed by flatwise curved strips of magnetic material. Surrounding the outer surface of the core there is provided a core clamp construction 29 which is similar to that illustrated in Fig. 3, except that it is more generally rectangular in shape so as to suitably fit the outer surface of the generally rectangularly shaped core 28. Surrounding the core member there is provided a suitable number of turns providing a secondary winding 30. A bolt 31 is placed between the outwardly extending arms 32 of the core clamp construction 29 for relatively tightly binding the core clamp around the core.

It will be seen that in the construction illustrated in the drawing and described above, I have provided a cradle clamp construction for supporting the core as well as providing a base or supporting structure for the apparatus.

Although I have shown and described particular embodiments of my invention, I do not desire to be limited to the particular embodiments described, and I intend in the appended claims to cover all modifications which do not depart from the spirit and scope of my invention.

What I claim as new and desire to secure by Letters Patent of the United States, is:

1. An electromagnetic induction apparatus including a toroidally shaped core formed of a flatwise curved strip of magnetic material, core clamp means including a metallic member embracing the outer periphery of said core, a winding around said core and clamp, insulating means between said core clamp and said winding for positioning said clamp on said core and for insulating said clamp and core from said winding, and means integral with said core clamp for providing a supporting base for said apparatus.

2. An electromagnetic induction apparatus including a toroidally shaped core, cradle core clamp means including two arms adjacent and having the same general contour as the outer surface of said core, a winding surrounding said core and core clamp, said core clamp having integral feet for providing a base for said apparatus.

3. An electromagnetic induction apparatus including a toroidally shaped core, a winding on said core, core clamp means including a member surrounding the outer periphery of said core inside said winding, means for binding said core clamp member relatively tightly around the outer periphery of said core, and means including integral feet extending from said core clamp member for providing a supporting base for said apparatus.

10 4. An electromagnetic induction apparatus including a closed core, a winding on said core, core clamp means including a member surrounding the outer periphery of said core under said winding, means for binding said core clamp member relatively tightly around the outer periphery of said core, and means including feet extending from said core clamp for providing a supporting base for said apparatus.

20 5. An electromagnetic induction apparatus including a closed laminated core having radially superposed layers of flatwise curved magnetic strip material, a core clamp having means which closely embraces a substantial part of the outer periphery of said core, integral feet members on said clamp for providing a supporting base for said apparatus, and an insulated electrical winding wrapped around both said core and clamp except where said feet extend away from said clamp.

30 6. In combination, a ring-shaped magnetic core of radial superposed lamination layers, a core clamping band surrounding the outer lamination layer, a winding around said core and clamping band, and means including feet extending from said clamping band for providing a base for said core and winding.

FRANKLIN R. D'ENTREMONT.
